Primary Examiner — Ricky Pham

(57) **CLAIM**

The ornamental design for a compact snacking utensil, as shown and described.

DESCRIPTION

FIG. 1 is a front perspective view of a compact snacking utensil showing my new design;

FIG. 2 is a back perspective view thereof;

FIG. 3 is a bottom plan view thereof;

FIG. 4 is a top plan view thereof;

FIG. 5 is a left elevational view thereof;

FIG. 6 is a right elevational view thereof;

FIG. 7 is a back elevational view thereof; and,

FIG. 8 is a front elevational view thereof.

1 Claim, 5 Drawing Sheets(56)
